CONTAINER FOR A BOW OR THE LIKE

Kenneth Reiner, 54091 Terminal Annex,
Los Angeles, Calif.

Filed Feb. 14, 1964, Ser. No. 78,639

Term of patent 14 years

(Cl. D58—13)

I claim:

The ornamental design for a container for a bow or the like, as shown.
